(57) **CLAIM**

The ornamental design for an vehicle air vent fin ashtray and smoking article holder, as shown and described.

DESCRIPTION

FIG. 1 is a front elevation view of my new design for an vehicle air vent fin ashtray for a smoking article in a configuration showing an environment of use holding the smoking article;

FIG. 2 is a front elevation exploded view thereof;

FIG. 3 is a plan rear view thereof;

FIG. 4 is a plan front view thereof;

FIG. 5 is a top, front perspective view of the vehicle air vent fin ashtray and smoking article holder;

FIG. 6 is a bottom plan view thereof; and,

FIG. 7 is a left side view thereof and the right being a mirror image.

The broken lines in the drawing depict environment of the vehicle air vent fin ashtray and smoking article holder that form no part of the claimed design.
